UNITED STATES PATENT OFFICE.

GAETANO MARCHESINI, OF NEW YORK, N. Y.

DESIGN FOR AN AUTOMOBILE-HORN.

No. 38,499.

Specification for Design.

Patented March 26, 1907.

Application filed February 14, 1907. Serial No. 357,418. Term of patent 7 years.

To all whom it may concern:

Be it known that I, GAETANO MARCHESINI, a citizen of the United States, residing at the city of New York, borough of Manhattan, in the county and State of New York, have invented a new, original, and ornamental Design for an Automobile-Horn, of which the following is a specification, reference being had to the accompanying drawings, forming part thereof, and in which—

Figure 1 is a side view showing an automo-

bile-horn incorporating my design. Fig. 2 is a top view thereof, and Fig. 3 is a rear end view of the same.

I claim—

The ornamental design for an automobile-horn, as shown.

GAETANO MARCHESINI.
